SUSPENDED CEILING HANGER

Daniel E. Danielson, Milwaukee, Wis.

Application September 3, 1931. Serial No. 560,913

2 Claims. (Cl. 72—118)

This invention relates to improvements in suspended ceiling hangers, particularly for use in connection with concrete building construction work.

5 In concrete building construction work the ceiling is usually suspended below the beams of the floor thereabove to provide a space between the ceiling and the floor for the disposition therein of conduits, pipes, wires, and so forth. The 10 ceiling is composed of suspended horizontal channel iron members, to the lower surfaces of which are tied laths or a plaster base, and then the usual plaster layer is applied to the lower or under surface of the laths.

15 The present invention aims particularly at a construction for suspending the horizontal ceiling channel iron members from the floor beams and one of the objects is to provide members for anchorage in the beams having integral malleable portions to be readily bent down and tied or secured about the channel irons which are to be suspended.

20 A further object of the invention is to provide suspended ceiling hangers which may be secured to the form boards and then cast directly in lower portions of the floor beams in a manner so that portions will be firmly embedded in the cast beams, while other portions may be bent entirely free of the beams for suspension purposes.

25 A further object of the invention is to provide suspended ceiling hangers which are easily installed and which may be secured to ceiling elements very readily and with a minimum of effort, which are relatively simple and inexpensive, which are strong and durable, and which are well adapted for the purposes described.

With the above and other objects in view the invention consists of the improved suspended 40 ceiling hanger, and its parts and combinations as set forth in the claims, and all equivalents thereof.

In the accompanying drawing in which the same reference characters indicate the same 45 parts in all of the views:

Fig. 1 is a sectional view through a concrete floor and floor beams showing the installation of the improved ceiling hangers in the cast beams and the manner in which a ceiling is suspended thereby;

Fig. 2 is a sectional view of the same taken on line 2—2 of Fig. 1;

Fig. 3 is an enlarged side view of an improved suspended ceiling hanger in the arrangement in 55 which it is secured to a form and cast in a beam,

part being broken away and in section to show details of construction;

Fig. 4 is an inverted plan view of the suspended ceiling hanger;

Fig. 5 is a sectional view taken on line 5—5 of Fig. 3 and on a larger scale; and

Fig. 6 is an enlarged fragmentary side view of one end portion of the device with the frame strip being shown in section.

Referring now more particularly to the drawing it will appear that the ceiling hanger comprises an elongated frame strip 8, preferably of semi-circular form in cross-section and having its lower edge formed with a longitudinally extending groove or recess 9. Said frame strip 8 is preferably formed of wood, but it is contemplated that the same may be formed to advantage of sheet metal, fiber or paper board, or of composition. Also, said strip may be of any suitable length, dependent upon the particular building conditions. Adjacent each end portion of the strip 8 there is formed therethrough at right angles to the recess 9 and opening into the same, a bore or aperture 10, said bores or apertures 10 at opposite ends of the strip being laterally off-set from one another, as best shown in Figs. 4 and 5.

The frame strip 8 serves as a housing and support for a pair of anchoring and suspending elements. Each of said elements is formed of 25 bendable wire bent to form a looped anchoring portion 11. The looped portion of an element is disposed in upright position adjacent the upper end portion of the strip 8 aligned with an aperture 10 and with its plane at right angles to the 90 vertical longitudinal plane of the strip. Two thicknesses of wire are depended from the looped portion 11 through the aperture 10 and then at right angles flatly within the recess 9 of the strip and longitudinally of the same. Said thicknesses 95 of each element within the recess 9 form suspending ties and are designated by the numerals 12. It will therefore be apparent that each suspended ceiling hanger comprises a frame strip and a pair of anchoring and suspending elements. 100 Said anchoring and suspending members are so disposed that each end portion of the strip has an anchoring loop of one of the elements projecting therefrom, and the double ply suspending ties of both elements extend adjacent each 105 other longitudinally in opposite directions within the recess of the strip.

A portion of a building construction with which the present invention is concerned is illustrated by Figs. 1 and 2 wherein a cast concrete floor 110

is designated by the numeral 13 and the concrete, depending floor beams by the numerals 14. During construction work, form boards to provide molds are suitably arranged to have concrete poured thereinto. The bottom form boards for the beams have nailed to their inner faces at suitable intervals, the frame strips 8. After the concrete for the floor and beams has been poured and becomes "set", the form boards are removed, and the frame strips and elements embodied therein are left embedded or cast in the lower portions of the beams 14, immediately adjacent the lower faces of the same, as shown. Staples 15 which are used to hold the tie portions 12 flatly within the recesses 9 are removed and then the pair of ties 12 of each element are bent downwardly vertically away from the beam, each pair of ties being bent with respect to its anchoring loop 11 at about the points indicated at 16. The ties 12 as thus depended serve to suspend channel iron ceiling members 17 which are extended transversely of the beams 14, and the lower free ends of each pair of tie portions 12 are bent about a portion of a member 17 and are secured as shown. Any number of ceiling members 17 are suspended at spaced intervals as described, and below the members 17 are channel iron members 18 extended transversely to the members 17 and tied thereto by wrapping wires 19. Laths or a plaster base 20 are suitably anchored to the undersurfaces of the ceiling members 18 and then plaster 21 and other finishing material is applied to the laths to form the finished ceiling.

It will therefore be seen that by means of the invention very simple and efficient means are provided for suspending a ceiling from the cast floor beams in concrete construction work. The ceiling hangers provide a permanent anchored connection between the beams and the ceiling elements and are easily and conveniently cast into the beams without any additional work. When required, the tie portions 12 are readily bent into position to be secured about the channel iron members. The arrangement is also such

that any desired distance may be left between the ceiling and floor.

While the improved ceiling hanger has been described particularly in connection with cast floor beams, it is obvious that it is also adaptable to beam and slab, concrete joist and tile, and other constructional arrangements.

The improved suspended ceiling hanger is also of simple and novel construction, and is well adapted for the purposes described.

What I claim as my invention is:

1. In combination, a building element having an outer surface, and a pair of combination anchoring and spacing members, each of said members having an enlarged anchoring end portion and an integral elongated rod portion with the rod portion being bendable with respect to the anchoring portion, the anchoring portions of said members being spacedly embedded in said building element with the rod portions of the two members extending flatly adjacent the outer surface of the building element in overlapping relation, said rod portions being bendable free of the building element surface for variable spacing connection with separated portions of a second building element.

2. In a building construction, a floor, a ceiling, and means for variably suspending the ceiling from the floor and out of rigid engagement therewith, comprising a pair of anchoring and suspension elements, each having an enlarged anchoring end portion and an elongated bendable tie portion, and an elongated, open-faced frame for the pair of elements with the anchoring end portions of the pair projecting from opposite end portions of the frame, the frame being embedded in the floor with its open face adjacent an outer surface of the floor and the anchoring end portions embedded in the floor, the ties being in a depending vertical position and having their end portions secured to elements of said ceiling, the ceiling being otherwise entirely free of and spaced from said floor.
